UNITED STATES. PATENT OFFICE.

ROBERT W. DAVIS AND ARTHUR W. DAVIS, OF ELMIRA, ASSIGNEES TO
SIDNEY SWEET, OF DANSVILLE, NEW YORK.

ROLLER SPRING-TOOTH HARROW AND CULTIVATOR.

SPECIFICATION forming part of Letters Patent No. 329,371, dated October 27, 1885.

Application filed October 7, 1884. Serial No. 144,903. (No model.)

To all whom it may concern:

Be it known that we, ROBERT W. DAVIS and ARTHUR W. DAVIS, of Elmira, in the county of Chemung, in the State of New York, have invented new and useful Improvements 5 in Roller Spring-Tooth Harrows and Cultivators, of which the following, taken in connection with the accompanying drawings, is a full, clear, and exact description.

This invention consists, first, of a harrow composed of separate and distinct frames detachably connected, and each equipped with operating-teeth arranged in such a manner that by disconnecting the frames from each other and connecting suitable handles to the detached frames the harrow is converted into convenient and efficient cultivators; and the invention further consists in certain peculiarities in the details of the apparatus, all as 20 hereinafter more fully described, and specifically set forth in the claims.

The invention is fully illustrated in the accompanying drawings, wherein Figure I is a side elevation of our improved roller spring-tooth harrow and cultivator combined. Fig. II is a plan view of the same. Fig. III is a rear end view. Fig. IV is a vertical transverse section on line xx , Fig. II. Fig. V is an enlarged top view of the attachment of the spring-tooth to the frame. Fig. VI is a vertical section of the same through the center thereof. Fig. VII is an enlarged side elevation of the spring-tooth and its attachment to the frame. Fig. VIII is an enlarged sectional view of the 35 attachment of the rollers to the frame; and Fig. IX is an enlarged transverse section of the spring-tooth, taken through the center of the attachment of the operating-point on line yy , Fig. VII.

40 Similar letters of reference indicate corresponding parts.

A A' A" represent three separate and distinct harrow or cultivator frames, one of which is arranged in advance of the other two, 45 and is composed of a long rear cross-bar, a shorter cross-bar in front of it, a still shorter cross-bar in front of the latter, and longitudinal beams A''' A''', connected to the central portions of the aforesaid cross-bars. The 50 rear cross-bar of the said frame forms lateral

extensions A'' A", to the ends of which the rear frames A' A', are respectively detachably connected. These rear frames are each composed of a long cross-bar, a shorter cross-bar at the rear, a still shorter cross-bar at the 55 front, and longitudinal beams A''' A''', connected to the central portions of the aforesaid cross-bars. Each of said frames is equipped with a set of spring-teeth, D D, the teeth of the forward frame being arranged in the following order, to wit: To each end of the forward and shortest cross-bars is attached one of the teeth D, equidistant from the center of the frame. To the ends of the intermediate cross-bar is attached another set of teeth, arranged a sufficient distance outward from the track of the forward teeth to leave between them an undisturbed strip of land for the carrying-wheels B B of the harrow to travel on. One tooth is attached to the center of the 60 rear and long cross-bar, and thus cultivates the strips of land left between the furrows formed by the teeth of the forward and shortest cross-bar, and at each side of the center of the rear cross-bar is secured a tooth in such a 65 position in relation to the teeth in front of it as to cultivate the strip of land left undisturbed between them and traveled over by the carrying-wheel B, hereinafter described.

The teeth of the rear frame are arranged as 70 follows, to wit: Two teeth are attached to the forward and shortest cross-bar, respectively at opposite sides of the center thereof, one tooth is attached to the center of the rear cross-bar, and two teeth on the same bar arranged outside of the track of the teeth of the forward cross-bar, and two more teeth are attached to the intermediate cross-bar and arranged outside of the outer teeth of the rear cross-bar. Thus each frame carries a complete set of teeth, occupying one-third of the 75 width of the entire harrow. The rear frames, being narrow, can, when detached from each other and from the forward frame, be used as two cultivators by attaching thereto suitable handles, which may be of any well-known form and attached in any ordinary and well-known manner, and therefore need no illustration in this case. Each of the aforesaid frames is supported independent of the others 80

by a set of carrying wheels or rollers, B B, which are arranged inside of the track of the outer teeth D and directly in front of two of the inner teeth, thereby bringing the said 5 rollers sufficiently near the center to allow the harrow to rock laterally and conform to the unevenness of the ground, and also harrowing the track made in the ground by the rollers. Said rollers are mounted loosely on opposite 10 ends of the axle a, to which are affixed two hangers, H H, which are applied to opposite sides of the central longitudinal beams, A' A' A', between the rear and intermediate cross-bars of the frame, and are provided with vertical slots d, through which and through the aforesaid beams the attaching-bolt e passes, said bolt being provided with a nut by which 15 to clamp the hangers H H on the beams of the frame, as illustrated in Figs. IV and VIII of the drawings. By loosening the nut of the bolt e the hangers H H can be raised or lowered, and thus the rollers B B can be adjusted to allow the teeth to enter the ground the desired depth, and in this adjusted position the 20 rollers are retained by tightening the aforesaid nut of the bolt e. The aforesaid rollers B B are of such diameters as to cause them to project above all parts of the harrow, thereby making said rollers support the harrow when 25 turned upside down, and thus facilitating the moving of the harrow to and from the field.

The teeth D we prefer to construct of two 30 separate and distinct spring-steel bars or heavy wires, each of which is formed into a vertical coil, e, terminating at one end with an arm, b, which projects tangentially from the lower portion of the coil and constitutes one of the attaching-shanks of the tooth. From the opposite end of the coiled portion e the spring-bar 35 is curved into an eccentrically-prolonged arm, which extends rearward above the frame, thence downward and forward and terminates below the frame, said two spring-bars being curved alike, so as to run parallel with each 40 other, and to their lower ends is attached the operating-point E, which consists of a vertically-elongated concavo-convex steel plate, pointed at opposite ends, so as to admit of reversing the plate end for end when one end 45 is worn out. Said plate is detachably connected to the two spring-bars of the tooth D by laying the point E with its concave side on the front of the two spring-bars and applying 50 against the back of said spring-bars a washer, f, which is provided with vertical grooves r r, in which the ends of the spring-bars lie. A bolt, g, passes through the point E and through the washer f, between the two spring-bars, and is provided with a nut, u, by which 55 60 said parts are clamped together, as shown in Fig. IX of the drawings. The two attaching-shanks b b of the two spring-bars are secured to the under side of the bar of the harrow-frame by means of a clamping-plate, h, placed 65 across said arms, and provided with grooves i i, in which the shanks b b lie. A washer or

stay-plate, k, is placed on the upper side of the frame and fastened thereto by a bolt, l, passing through the plates h and k and intervening frame-beam, and provided with a nut, 70 as shown in Fig. VI of the drawings. The plate k is provided with recesses or ways m m, through which the coils e e of the teeth D pass. The bearings of the coils in said recesses serve to sustain the coils in their vertical position, 75 and thus brace the tooth to some extent laterally. A harrow-tooth formed of two spring-bars in the manner aforesaid is capable of yielding laterally as well as rearwardly when encountering immovable obstructions in the 80 ground, and instead of throwing stones to the surface said tooth will spring aside from the stones and leave them under the surface of the ground, and in springing aside, as aforesaid, the tooth thoroughly stirs up the ground and 85 pulverizes it.

S denotes the driver's seat, which is sustained in its position above the harrow by means of braces T T T, consisting of spring-metal bars, which render the seat-support 90 elastic, and rest with their feet on the central portions of the three frames A A' A', as shown by full lines in Figs. I and III of the drawings and by dotted lines in Fig. II of the drawings. The weight of the driver is thus 95 distributed over the three frames. Whenever it is desired to use the two rear frames or sections, A' A', of the harrow for cultivators, the seat S is to be removed, and the two sections A' A' are to be uncoupled from each 100 other and from the forward frame, A, and suitable handles are to be connected with the respective sections or frames A' A'. The coupling device between the forward and rear frames, A A', can be used for attachment of 105 the whiffletree to the rear frames. The seat-supporting braces T T T are detachably connected to the harrow-frame, so that when the harrow is to be turned over onto its back the seat, with its braces, can be removed and subsequently secured to the inverted harrow, to allow the driver to ride to and from the field. 110

We are aware that land-rollers have been connected with a harrow-frame in such a manner as to project above said frame, and thus allow the apparatus to be used either as a harrow and land-roller combined, or simply as a land-roller by turning it over; but it is obvious that the turning over of such a device is a very difficult operation, owing to the 115 great length and weight of the rollers. In our improved harrow the rollers are simply carrying-wheels having a comparatively narrow tread, and arranged near the longitudinal central line of the frame, and therefore allow the 120 harrow to freely rock laterally and to be easily turned over when desired.

Having described our invention, what we claim as new, and desire to secure by Letters Patent, is—

1. A harrow composed of separate and distinct frames detachably connected, and

each provided with a set of teeth and supported independently of the other by rollers connected with said frame, substantially as set forth and shown.

5. 2. A roller-harrow composed of three separate and distinct frames, each equipped with a set of spring-teeth, one of said frames being arranged in advance of the others and provided at opposite sides with lateral extensions, the two rear frames being detachably connected to said extensions, carrying-rollers connected with the respective frames, and the driver's seat supported on braces resting with their feet respectively on the three frames, substantially as described.

15. 3. The combination of the harrow-frame composed of cross-bars and longitudinal bars attached to the central portion of said cross-bars, an axle secured across the longitudinal bars, carrying-rollers on said axle, teeth attached to the forward cross-bars at points inside and outside of the line of travel of the rollers, a tooth attached to the rear cross-bar central between the tracks of the rollers, and teeth attached to said cross-bar in range with the track of the rollers, substantially as described and shown.

20. 4. The harrow composed of a long cross-bar, a shorter cross-bar at the rear, a still shorter cross-bar in front, longitudinal beams connected to the central portions of the cross-bars, two teeth attached to the front cross-bar respectively at opposite sides of the center thereof, a tooth attached to the center of the rear cross-bar, and two teeth on the same bar arranged outside of the teeth of the forward cross-bar, and two teeth on the intermediate cross-bar arranged outside of the outer teeth of the rear cross-bar, substantially as described and shown.

25. 5. The combination of the harrow-frame composed of three separate and distinct frames, each equipped with a set of spring-teeth, one of said frames being arranged in advance of the

others and provided at opposite sides with lateral extensions, the two rear frames being detachably connected to said extensions, carrying-rollers connected with the respective frames, and the driver's seat supported on braces resting with their feet respectively on the three frames, and an axle extended across the longitudinal bars between the central and rear cross-bars, and rollers on said axle in front of and in range with the outer teeth of the rear cross-bar, substantially as described.

5. 6. The forward harrow-frame, composed of a long rear cross-bar, a shorter cross-bar in front of it, a still shorter cross-bar in front of the latter, longitudinal bars connected to the central portion of the cross-bars, teeth on the ends of each of the two front cross-bars, one tooth in the center of the rear cross-bar, and two teeth on the latter at opposite sides of the center and in line with the center of the space between the tracks of the forward teeth, in combination with harrows at the rear of and detachably hung on the ends of the rear cross-bar of the forward harrow, substantially as described and shown.

7. 7. A harrow composed of separate and distinct frames detachably connected, and each provided with a set of teeth and supported independently of the others by rollers connected with the frames, and a driver's seat supported by braces resting with their feet centrally on the respective frames, substantially as set forth.

In testimony whereof we have hereunto signed our names and affixed our seals, in the presence of two attesting witnesses, at Elmira, in the county of Chemung, in the State of New York.

ROBERT W. DAVIS. [L. S.]
ARTHUR W. DAVIS. [L. S.]

JAMES R. REID,
CHAS. G. LAPPE.

It is hereby certified that in Letters Patent No. 329,371, granted October 27, 1885, upon the application of Robert W. Davis and Arthur W. Davis, of Elmira, New York, for an improvement in "Roller Spring-Tooth Harrows and Cultivators," an error appears in the printed specification requiring correction as follows: In line 131, page 2, the word "hammer" should be stricken out and the word *harrow* inserted instead; and that the said Letters Patent should be read with this correction therein that the same may conform to the record of the case in the Patent Office.

Signed, countersigned, and sealed this 3d day of November, A. D. 1885.

[SEAL.]

H. L. MULDROW,
Acting Secretary of the Interior.

Countersigned:

M. V. MONTGOMERY,
Commissioner of Patents.
